UNDERGROUND ANTENNA BURIED IN
FROZEN SOIL

D'Arcy A. Shock, Warren W. Woods, and Henry F. Coffer, Ponca City, Okla., assignors to Continental Oil Company, Ponca City, Okla., a corporation of Delaware

Filed Jan. 21, 1963, Ser. No. 252,755
3 Claims. (Cl. 343—719)

The present invention relates to method and apparatus for electrically insulating a buried conductor and more particularly, but not by way of limitation, relates to a novel radio antenna and method for constructing same.

As is well known, so-called "hard" military bases, such as missile sites, which are considered invulnerable to anything but a direct hit by an atomic warhead, are presently being designed and constructed. Invulnerability is most commonly achieved by placing all essential structures below ground level so that they will escape the tremendous blast forces as well as the radiation effects of heat and atomic particles which may be caused by a near-miss. The construction of such a site is complicated by the fact that every military installation depends heavily upon a communications system. Laying of underground cables and telephone lines over the vast distances required for proper deployment of the military installations would be prohibitive in cost. Therefore, it is essential that some type of radio communications system be provided which can be entirely buried, including the antenna. One type of radio communications system which is especially well adapted for this type of installation utilizes an antenna comprised of a plurality of electrical conductors buried several feet below the surface of the earth and arrayed in some suitable pattern covering an area of several thousand feet square, depending upon the particular frequency being used. In the operation of this radio equipment, it is important that the buried conductors of the antenna be essentially insulated from the surrounding soil and that the conductance of the soil surrounding the antenna be maintained substantially constant at the low conductance value. Almost all soils are highly conductive when moist because the moisture normally becomes saline as a result of dissolved salts and minerals which produce a highly conductive ionic solution. The problem is further complicated by the fact that as the moisture content of the soil varies from period to period or season to season, the conductivity of the soil also varies so as to sometime interfere with the adjustments of the communications systems.

Therefore, it is an important object of the present invention to reduce the electrical conductance of the soil around a buried electrical conductor, such as an antenna, to a minimum and to maintain the minimum conductance substantially constant.

Another object of the present invention is to provide a microwave antenna which is materially protected from destruction by enemy attack.

Still another object of the present invention is to provide a method for constructing a microwave antenna of the type described.

Many additional objects and advantages of the present invention will be evident to those skilled in the art from the following detailed description and drawings, wherein:

FIG. 1 is a vertical sectional view, somewhat schematic, of an antenna constructed in accordance with the present invention;

FIG. 2 is a plan view, somewhat schematic, of the device of FIG. 1;

FIG. 3 is a sectional view, somewhat schematic, which

2

serves to illustrate a portion of the structure of the device of FIG. 1; and,

FIG. 4 is a graph showing the conductance of a typical saline soil plotted against temperature.

Referring now to the drawings, and in particular to FIGS. 1 and 2, an antenna constructed in accordance with the present invention is designated generally by the reference numeral 10. The antenna 10 comprises a plurality of conductors 12 which are buried in and therefore surrounded by soil 14. The conductors 12 may be arrayed in the most suitable pattern for maximum electromagnetic propagation and reception, the particular optimum pattern being dependent upon the frequency and design of the particular radio communications system

15 for which the conductors 12 form the antenna in accordance with design considerations which are well known in the art. However, for purposes of this disclosure, it is sufficient to note that the conductors 12 are arrayed within the general confines of the dotted outline 16 as shown in FIG. 2.

The soil 14 may be virtually any soil, and will in most cases be the native soil of the particular locality. Most native soils have sufficient moisture to be readily frozen but in some instances it may be desirable to add some

25 moisture so that the soil can be more easily frozen at low temperatures. The moisture within the soil will invariably be saline at least to a certain extent due to dissolved salts and minerals and accordingly the soil would normally have a relatively high specific conductance. However, in

30 accordance with the present invention, the temperature of soil 14 is reduced until the area around antenna 10 is substantially completely frozen and the ionic salts and minerals within the solution are immobilized and the soil made essentially nonconductive. FIGURE 4 is a graph showing the specific conductance of a saturated NaCl solution plotted against temperature. It will be noted that the specific conductance decreases linearly as the temperature is lowered from 0° C. to -30° C. and that the

35 slope of the plot is such that by simple extrapolation it would appear that the conductance of the solution could not be lowered to a significant value without reducing the temperature to a completely impractical value. However, we have discovered that by reducing the temperature further, the specific conductance begins to be reduced at a

40 much greater rate below approximately -40° C. such that at attainable temperatures the specific conductance of a salt solution and therefore of a moisture laden soil can be reduced to a very small value and the total conductance

45 of the soil around the electrical conductors 12 reduced to substantially zero, assuming that a reasonably large thickness of the frozen soil is available for insulation purposes. Therefore it is to be understood that in the antenna installation 10 the soil 14 is at a temperature

50 sufficiently low as to have the desired low conductance value, or conversely, the desired high insulation value. The particular temperature necessary for a specific antenna installation will vary to some degree from location to location but can be determined at each site merely

55 by lowering the temperature of the soil and measuring the specific conductance so as to obtain a graph as shown in FIG. 4, and then computing, by normal engineering methods, the necessary temperature and thickness of frozen soil required to attain the desired level of insulation.

60 A suitable refrigeration means, indicated generally by the reference numeral 18, is provided to freeze and maintain the soil 14 at the low temperature. The refrigeration means 18 may be comprised of any suitable refrigeration system and does not per se comprise a part of the present invention. One type of refrigeration system which has been successfully used for freezing the earth in other ap-

plications utilizes the expansion of a liquefied refrigerant such as propane. The propane may be mechanically compressed by suitable compressor apparatus represented schematically and designated by the reference numeral 20. The compressed propane may then be circulated sequentially through a series of refrigerator pilings 22 by suitable interconnecting conduits 24 and expanded to produce cooling. Each refrigerator piling 22 is comprised essentially of an external casing 26 and an inner conduit 28 which extends to a point adjacent to the bottom of the casing. The inlet conduit 24 for passing the refrigerant into each refrigerator piling 22 is connected to the inner conduit 28. The next successive conduit 24 which serves as an outlet for the particular refrigerator piling is connected to the upper end of the casing 26 at an outlet point 30 and is then connected to the inner conduit 28 of the next succeeding refrigerator piling 22, as best seen in FIG. 3 wherein like components of each of the refrigerator pilings 22 are indicated by the same reference numerals.

Therefore, referring once again to FIG. 2, the refrigerant is circulated from the apparatus 20 successively through the refrigerator pilings 22_a-22_p in alphabetical sequence and thereby continually maintains the soil 14 frozen both above and below the conductors 12 and for a considerable distance around the periphery of the electrical conductors 12 which, as previously mentioned, are arrayed within the confines of the dotted outline 16 of FIG. 2 in order to lower the conductance of the soil to a minimum value. It will be noted that the refrigerator pilings 22 extend to a substantial depth below the conductors 12 as best seen in FIG. 1, so as to freeze the soil to a considerable depth and thereby reduce heat transfer from the surrounding earth formation due to the fact that the frozen earth is a good thermal insulator. In order to prevent heat transfer from the atmosphere into the frozen soil 14, a layer of expanded perlite 34 may cover the entire area over which the soil 14 is frozen. A water impervious film 38, such as asphalt or a suitable plastic, may then be placed over the perlite insulation both to trap a quantity of dead air space within the expanded perlite and to prevent the intrusion of surface water into the zone of frozen soil. In the absence of camouflage requirements, the water impervious film 38 is preferably covered with a white or heat reflecting layer of material 40 which may be chipped white rock, or a suitable silvered coating on the water impervious film 38.

One method by which the antenna installation 10 may be constructed in accordance with the method of the present invention is as follows. The conductors 12 of the antenna proper are imbedded in the earth in the desired array by any suitable means such as by ditching and back covering. A number of vertical bores are drilled in the soil 14 for receiving the refrigerator pilings 22. The bores may be drilled in any suitable pattern but preferably are drilled in some predetermined and organized pattern such as is illustrated in FIG. 2 wherein the bores are represented by the dotted circles 44. A plurality of refrigerator pilings 22 may then be inserted in the two center rows A and B of bore holes 44 and interconnected by suitable conduits 24 as represented by the dotted lines 46. The refrigerant is then circulated through the conduit 24 and the refrigerator pilings 22 disposed in the well bores of rows A and B until the soil 14 is lowered to the desired temperature. After the temperature of the soil between and to a distance on each side of the rows A and B has

been lowered to the desired value, the refrigerator pilings 22 are withdrawn from the bore holes and are moved to the bore holes of rows C and D. The conduits 24 are again connected as previously described along the dotted lines 48 and the refrigeration process repeated. It will be noted that four more refrigerator pilings 22 are required for this step. After the soil 14 has been lowered to the desired temperature, the center four pilings on the two sides are withdrawn from the respective well bores 44 and moved outwardly to the well bores 44 in rows E and F. All refrigerator pilings 22 will then be in the permanent positions for the completed antenna installation. The conduits 24 are then permanently connected between the several refrigerator pilings and the final outside ring of the soil 14 lowered to the desired temperature. Of course, during the several steps of freezing the soil in rings, the soil in the center is maintained at the desired low temperature.

As the refrigerator pilings 22 are withdrawn from the innermost well bores 44, the well bores are filled with soil or with a suitable insulating material such as expanded perlite. The layer of insulating material 34 is spread over the entire installation and then covered with the suitable moistureproof film 38 of plastic or asphalt either before or after the freezing steps. The layer of reflecting chips or other surface may be similarly applied if required. Continued operation of the refrigeration device with the refrigerator pilings 22 in the desired positions maintains the soil 14 within the boundaries defined by the outline 36 at the desired low temperature. The insulation of the earth around the block of frozen soil and the insulation applied to the surface serve to substantially reduce the heat exchange with atmosphere and the earth.

We claim:

1. An antenna installation comprising:
a quantity of soil at a temperature below about -30° C.,
a plurality of interconnected freeze points arranged in a closed pattern surrounding at least a portion of said soil, for maintaining said soil at a temperature below about -30° C.,
means communicating with said freeze points for furnishing refrigerant thereto at a temperature below -30° C., and
a plurality of horizontally disposed conductors embedded in said soil at a position within said closed pattern of freeze points and below the surface of said soil.
2. The antenna defined in claim 1 further characterized by a quantity of heat insulating material overlying said conductors.
3. The antenna defined in claim 2 further characterized by a water-impervious film overlying said heat insulating material.
